UNITED STATES PATENT OFFICE.

JAMES H. YOUNG, OF PITTSBURGH, PENNSYLVANIA.

CONTAINER FOR RAZOR BLADES.

Application filed February 9, 1923. Serial No. 617,908.

To all whom it may concern:

Be it known that I, JAMES H. YOUNG, a citizen of the United States, residing at Pittsburgh, in the county of Allegheny and State of Pennsylvania, have invented a new and useful Improvement in a Container for Razor Blades, of which the following is a specification.

This invention relates to a container for the blades of a safety razor.

The object of the invention is to provide a container for the blades of safety razors which is of attractive appearance and of durable material; which is capable of receiving a plurality of the blades while being sufficiently compact to occupy but little space within the case of a safety razor; and which is arranged to protect and preserve the cutting edges of the blades therein and to permit ready removal of the blades.

In the accompanying drawings Figure 1 is a plan view of the complete container; Figure 2 is a central vertical section therethrough; Figure 3 is a central vertical section through the body of the container; Figure 4 is a plan view thereof; Figure 5 is a central vertical section through the cover of the container; Figure 6 is a plan view thereof; Figure 7 is a cross sectional view on the line 7—7 Figure 4; Figure 8 is a cross sectional view through the cover of the container; Figure 9 is a plan view of a complete container of a modified form; Figure 10 is a central vertical section therethrough; Figure 11 is a central vertical section through the body of the container; Figure 12 is a plan view thereof; Figure 13 is a central vertical section through the cover of the container; Figure 14 is a plan view thereof; Figure 15 is a cross sectional view through the body of the container on the line 15—15, Figure 12; and Figure 16 is a cross sectional view through the cover of the container.

Both modifications of the device are composed of relatively thin sheet metal, preferably aluminum, which may be pressed to the desired form.

In the form of the device illustrated in Figures 1 to 8 inclusive of the drawings the body 1 of the container comprises a tray or blade containing portion 2, and a clamping portion 3 for securing the cover 4 of the container thereon.

Pressed up from the tray or blade containing portion 2 of the body of the container are posts or lugs 5, which are ar-

ranged to pass through apertures in the razor blades and accurately position the same in the container. Because of such positioning means the cutting edges of the blades are prevented from coming into contact with the side walls of the container, and dulling of these edges, due to agitation of the container or the safety razor case in which it is held is prevented. The walls of the tray 2 itself adequately protect the edges of the blades from injury due to contact with any external object. It will be understood that the blade positioning posts 5 may be formed separately from the tray 2 of the container if so desired, and may be secured to the bottom of the tray by soldering or in any other convenient manner. It is desirable however both for neatness and for manufacturing economy that the blade positioning posts or lugs be formed integral with the body of the container, as shown.

The cover 4 of the container is formed with a top 4^a, sides 4^b, and feet or flanges 4^c, which extend inwardly from the sides and are arranged to embrace the bottom of the tray 2. One end 4^d of the cover may be closed, as shown, while the other end 4^e is open so that the cover may be slipped over the tray portion 2 of the body 1. The cover 4^a clamping portion 3 of the body comprises a portion 3^a which extends rearwardly and has a depressed portion 3^b for receiving the top 4^a of the cover. This depressed portion 3^b is provided with a depending flange 3^c which forms the forward wall of tray portion 2, and on its upper surface is provided with a protuberance 3^d arranged to engage an indentation 4^f in the top 4^a of the cover.

In filling the container safety razor blades are laid in the tray portion 2 of the body in such manner that the posts or lugs 5 pass through the apertures in the blades which receive the positioning posts of the safety razor when the blade forms part of the assembly thereof. The body 1 of the container is of sufficient depth to accommodate three thin safety razor blades, together with thin strips of canton flannel or the like which may desirably be placed beneath, above, and between the blades. When the tray portion 2 of the body 1 has been filled with the blades, the cover 4 is slipped over the body so that it engages the clamping portion 3 thereof. In this position the cover is secured on the body by the natural resiliency of the metal of both thereof.

In order that blades may be readily removed from the container, a portion of the bottom thereof is pressed upwardly to form a platform 6 upon which the razor blades rest. It will be seen that this platform provides space at the end of blades for the insertion of the finger tips of a person desiring to remove the blades.

In the modified form of container shown in Figures 9 to 16 inclusive of the drawings the body of the container and its cover are identical with the form described above, except for the manner in which the cover of the container engages with the body thereof. Thus the body 7 of the container is provided with positioning posts 8 arranged to pass through apertures in the safety razor blades, and with a platform 10 pressed upwardly from the body of the container.

In this form of the container, however, the side walls 7^a of the body 7 are turned over to form lips or flanges 7^b, which are curved outwardly throughout their length, as shown in Figure 15 of the drawings. The cover 9 of this modified form of the container is also formed to embrace the body 7 thereof; so that, when the body has been filled with blades and the cover slipped thereon, it is held in place by its own resiliency and that of the sides 7^a and curved flanges 7^b of the body 7.

It will be readily understood that both forms of the safety razor blade container shown and described are durable and of attractive appearance. They also present the great advantage that they provide a permanent container which is capable of receiving several razor blades, and which is also so compact that it may be held in a pocket in a safety razor case of the pocket book type or in straps on the under side of the lid of a box for containing a safety razor.

It is also to be understood that various modifications from the forms of the device as shown and described may be made without departing from the spirit of the invention in its broader aspect. For example, various other forms of cover might be employed without impairing the utility of the other features of the invention as embodied in the appended claims.

What I claim is:

1. A container for perforated razor blades comprising a body of a resilient and highly malleable metal or tray, posts formed of the metal of the bottom of said body and arranged to receive a plurality of perforated razor blades and position the same in the body, curved flanges extending along the sides of said body, and a cover arranged to be held in place by the resiliency of the sides and the flanges of said body.

2. A container for perforated razor blades comprising a metallic body or tray, posts in said body for receiving and positioning perforated razor blades, a blade receiving platform covering part of the area in the bottom of said body, and a cover arranged to be secured to the body by the resiliency of the cover and the body.

3. A container for perforated razor blades comprising a metallic body or tray, posts formed of the metal of the bottom of said body and arranged to receive a plurality of perforated razor blades and position the same in the body, and a blade receiving platform pressed up from the metal of the bottom of said body and covering part of the area thereof.

4. A container for perforated razor blades comprising a metallic body or tray, posts formed of the metal of said body and arranged to receive a plurality of perforated razor blades and position the same in the body, a blade receiving platform pressed up from the metal of the bottom of said body and covering part of the area thereof, and a cover arranged to be secured to the body by the resiliency of the cover and the body.

5. A container for perforated razor blades comprising a metallic body or tray, posts in said body for receiving and positioning perforated razor blades, a blade receiving platform covering part of the area in the bottom of said body, curved flanges extending along the sides of said body, and a cover arranged to embrace said body and be held in place by the resiliency of the sides and the flanges of said body.

6. A container for perforated razor blades comprising a metallic body or tray, posts formed of the metal of the bottom of said body and arranged to receive a plurality of perforated razor blades and position the same in the body, curved flanges extending along the sides of said body, a blade receiving platform covering part of the area in the bottom of said body, and a cover arranged to be held in place by the resiliency of the sides and the flanges of said body.

7. A container for perforated razor blades comprising a body or tray, posts in the bottom of the body arranged to receive a plurality of perforated razor blades and position the same in the body, and a blade receiving platform covering part of the area of the bottom of the body.

In witness whereof, I hereunto set my hand.

JAMES H. YOUNG.
